CLAMPING DEVICE

Herbert D. Ayer, Fairfield, Maine

Application March 30, 1937, Serial No. 133,902

3 Claims. (Cl. 24—81)

This invention relates to an improved clamp and pertains particularly to a clamp for application to a metal roof.

The present invention has for its primary object to provide an improved clamp for application to a metal roof whereby a ladder or other structure may be mounted upon the roof and secured thereto through the medium of the clamp so as to prevent it moving or slipping under the weight of a body mounted on the ladder.

Another object of the invention is to provide an improved roof clamp which may be easily and quickly applied to one of the seams forming a part of the usual metal or tin roof, which will securely grip the seam so as to hold a ladder or other structure against slipping and without damaging the metal of the roof.

A still further object of the invention is to provide a novel roof seam engaging clamp in which two clamping members are provided which are adapted to engage over the seam and a pair of compressing members are pivotally attached thereto which will press the clamping members into gripping action with the seam so as to firmly hold the seam without injuring the same.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the appended claims.

In the drawing:

Figure 1 is a view in plan of a portion of a roof and a seam, showing the clamp embodying the present invention applied to the seam.

Fig. 2 is a view partly in side elevation and partly in longitudinal section of the clamp per se.

Fig. 3 is a view in transverse section on the line 3—3 of Fig. 1.

Fig. 4 is a plan view of a blank which is folded to form a part of the clamp structure.

Fig. 5 is a view in bottom plan of the central portion of the clamp device.

Referring now more particularly to the drawing the numeral 1 designates a portion of the metal roof, such roof being usually formed of strips of metal such as tin or copper, which have their adjoining edges secured together by an upstanding seam or ridge, which is indicated by the numeral 2 and which the present clamp device 55 grips when it is in use. The clamp is indicated

as a whole by the numeral 3, and comprises a main body portion 4 which consists initially of a blank A of metal such as is illustrated in Fig. 4 and which is of a substantial length and is cut inwardly longitudinally from each end, as indicated at 5, to form the two leg portions 6 and the solid central portion 7, which may be referred to as a saddle. The blank, after cutting in the manner shown in Fig. 4, is bent longitudinally through the saddle portion so as to bring the two arms 6 at each end into side-by-side relation, as is illustrated in Fig. 3. These arms thus become clamping members which are compressed, as hereinafter described, to grip between them the seam 2 of the roof.

The opposing inner faces of the clamping arms 6, of which there are two pairs as shown in Fig. 2, are covered by a suitable lining substance such as rubber or a rubberized fabric, as indicated at 8 in Fig. 3.

After forming the blank as described to bring the clamping arms 6 into side-by-side relation, there is secured to the top of the saddle portion 7, a saddle block 9 through which are passed the two pivot pins 10 each of which has pivotally attached thereto the spaced curved furcations 11 formed at the end of a channeled compressing bar 12. Each of these bars 12 is oscillatable upon a pin 10 and when moved in one direction straddles a pair of clamping arms 6 and, due to the transverse sectional configuration of the compressing bar, forces the clamping arms together when the bar is moved in the position relative to the clamping arms in which it is shown in Fig. 2.

Each of the compressing bars 12 is of greater length than the clamping arms so as to provide the end extension 13 which constitutes a handle by means of which the bar may be moved into or out of operative position.

Secured in any suitable manner to the centrally positioned saddle block 9 is a ring or eye 14, and when the ridge clamp is in position upon a roof ridge, as illustrated in Fig. 1, this eye may have coupled therewith the hooks 15 carried upon the ends of a section of chain 16, which has been passed around a rung 17 of a ladder, which is laid upon the surface of the roof between two ridges. It will thus be seen that a ladder placed upon a roof in the manner illustrated will be securely held against movement by the chain after it has been attached to the ladder in the manner described and has had its ends coupled with the clamp through the medium of the eye 14.

While the block 9 has been illustrated as having a ring or eye secured thereto, it is to be understood that the invention is not to be limited to this specific detail, as any other suitable means 5 of attaching a rope or chain to the clamp may be employed.

What is claimed, is:

1. A metal roof ridge engaging clamp, comprising a body having a pair of relatively long 10 spaced parallel clamping arms extending therefrom, said arms being of sufficient width to cover the sides of the roof ridge, a friction covering overlying the opposed faces of the clamping arms, a compressing bar of substantially U-shape cross- 15 sectional design and of greater length than the arms, means pivotally coupling one end of the bar with the body, the other end of the bar extending beyond the adjacent ends of the arms and constituting a handle facilitating the oscillation of the bar, and means for attaching a flexible 20 element to the body.

2. A roof ridge clamp, comprising a body having a central portion and two pairs of clamping arms extending in opposite directions therefrom, 25 said clamping arms being in spaced parallel relation and resilient to facilitate their being moved relative to one another, a pair of compressing bars each having a length greater than a pair of arms and each having a substantially U-shape 30 cross-sectional design, means pivotally coupling one end of each compressing bar with the central portion of the body whereby the bars extend

in opposite directions and in a manner to receive the adjacent pair of arms when oscillated toward the latter, the other end of each of said bars extending beyond the free ends of the adjacent arms and constituting an actuating handle, friction means lining the opposed faces of said gripping arms, and means for attaching a flexible coupling element to the central portion of the body. 5

3. A clamp, comprising an elongated member 10 consisting of a central portion of U-cross section and oppositely directed pairs of spaced parallel arms integral with said portion, the arms of one pair being longitudinally alined with the arms of the other pair and with the sides of the 15 central portion from which they project, said central portion having the back thereof set outwardly from the plane of the adjacent edges of the arms, an eye carried by said back of the central portion, and a compressing bar for each pair 20 of arms consisting of an elongated member of U-cross section having two curved ears projecting from one end to receive a portion of the said central portion and pivot means coupling the ears of each compressing bar with the central portion 25 whereby each bar may be oscillated in a direction to engage and compress the adjacent pair of arms therebetween and each compressing bar extending at its free end beyond the free ends of the arm engaged therein to provide a handle. 30
